UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

DESIGN FOR A LIGHTING UNIT.

Application filed July 14, 1924. Serial No. 10,145. Term of patent 14 years.

To all whom it may concern:

Be it known that I, CROMWELL A. B. HALVORSON, Jr., a citizen of the United States, residing at Lynn, in the county of Essex and State of Massachusetts, have invented a new, original, and ornamental Design for Lighting Units, of which the following is a specification, reference being had to the accompanying drawing, forming a part thereof.

The accompanying drawing is a perspective view of my new design.

I claim:

The ornamental design for a lighting unit as shown.

In witness whereof, I have hereunto set my hand this eleventh day of July, 1924.

CROMWELL A. B. HALVORSON, Jr.
